UNITED STATES PATENT OFFICE.

ABRAHAM O. FRICK, OF WAYNESBOROUGH, PENNSYLVANIA.

ROAD-ENGINE.

SPECIFICATION forming part of Letters Patent No. 243,881, dated July 5, 1881.

Application filed January 25, 1881. (No model.)

To all whom it may concern:

Be it known that I, ABRAHAM O. FRICK, of Waynesborough, in the county of Franklin and State of Pennsylvania, have invented a new and Improved Road-Engine; and I do hereby declare that the following is a full, clear, and exact description of the same, reference being had to the accompanying drawings, forming part of this specification, in which—

10 Figure 1 is a side elevation. Fig. 2 is a rear-end elevation, with the side plates, D, and sills A in vertical section. Fig. 3 are details of the counter-shaft bearings and transverse brace for the side plates. Fig. 4 is a top view of the 15 front support for the boiler. Fig. 5 is a front view of the same, with the sills A and the yoke-plate M in section. Fig. 6 is an end view of the same, with the axle in section; and Fig. 7 is a cross-section through line x x of Fig. 1.

20 My invention relates to certain improvements in road-engines, designed to improve the construction and operation of these devices.

The principal features of improvement consist in the structure of the frame-work and means for hanging the boiler therein to compensate for expansion; in the means for connecting the engine and the frame so as to avoid working-strain on the boiler-sheets; in 25 the construction and arrangement of the front truck, and in the means for guiding the engine, all as hereinafter more fully described.

In the drawings, A A represent a pair of iron sills, made in the form of channel-bars, as 30 shown in Figs. 2 and 5, (they may also be made of angle-iron or other shapes,) and extending the full length of the engine from the front truck to a point some distance in rear of the boiler. These two sills constitute the main 35 frame of the engine, and at the point where they extend beyond the rear of the engine they form a support for the platform for the use of the engineer and fireman, and a support also for the water-tank B, which is suspended from 40 the under side of the same. These sills A A, while constituting the main frame, are in no wise bolted or rigidly attached to the boiler, except at one point, a, where they are connected by angle-irons or brackets on each side. 45 There being but this one connected with the sills, it is obvious that the expansion and con-

traction of the boiler is in no wise affected by the said sills. The boiler is supported at other points by a loop or stirrup strap, C, hung to the sills in the rear, and by an expansion-joint 55 with the front truck, as will be hereinafter described. This stirrup or loop C carries the principal part of the weight of the boiler, and relieves the sheets of the boiler from all strain caused by carrying it in brackets or plates, 60 which are usually bolted to the sheets.

D D are metal side plates bolted or riveted to the iron sills on each side of the boiler, and extending vertically therefrom. Each of these plates has a slot or notch at its lower side, 65 which slips over the axle E to brace it and hold it in position, and has at the top two levels, the lower one of which carries the bearings F for the counter-shaft, and the upper one of which levels is bolted to the end of the 70 engine-frame G which carries the crank-shaft. This end of the engine-frame is formed like a saddle, which straddles the rear end of the boiler, but does not come in contact with it. The lower section of the two bearings F for the 75 counter-shaft are formed in one piece, being connected by a flanged and trough-shaped bar, F', which serves as a brace to connect the two side plates firmly together, as in Figs. 2 and 3. These side plates carry the weight of the rear 80 end of engine-frame, crank-shaft, fly-wheel, and pillow-block, and carry all the working-strain of engine and all the traction-gearing, thus entirely relieving the boiler of the same.

The engine-frame G, it will be seen, rests at 85 its back end upon the top of the side plates, as before described, while at its forward or cylinder end it rests upon the boiler. It is not rigidly attached to the boiler at this point, however, but has an expansion-joint to prevent strain occurring between the said frame and boiler, due to the heating and cooling of the latter. This joint is shown in Fig. 7, in which b is a casting riveted or bolted to the boiler, and c shouldered bolts which pass 90 through longitudinal slots in the flange of the engine-frame, so that after the bolts are tightly screwed down on their shoulders the engine-frame can still slide longitudinally, by reason of its slots, over the plate b, to permit the expansion and contraction of the boilers without strain. The plate b is provided with side 95 100

flanges to co-operate with the shoulder-bolts in preventing side movement.

For steering the engine, the front axle, H, is arranged to turn about a vertical center, and 5 a chain is attached to one side of the axle, and thence extends rearwardly to a roller or drum, I, around which it is wrapped several times, and is then returned to the axle on the other side of its pivot, so that by revolving the drum 10 one way or the other the chain is wound up on one side and unwound on the other to change the position of the front axle from a right-angular position to an oblique one, to cause the turning of the engine. This drum I extends 15 transversely across the machine beneath the boiler, and it is carried by hangers J, bolted to the main sills A. For rotating this drum a worm-wheel, d, is arranged at one end and a worm, e, made to gear therewith, which worm 20 is carried by a shaft, K, extending to the rear, and carrying, in convenient position for the engineer, a hand-wheel. This steering mechanism, as so far described, I do not claim as new. With such a chain-gear, however, I find that 25 when the front truck-axle is arranged obliquely the chain does not equally wind up on one side and unwind upon the other, and there is always some play in the axle-connections; and, furthermore, in running the wheels against ob- 30 stacles it sometimes happens that one front wheel will strike an obstruction and throw the axle around, leaving it in the position which causes the engine to run out of its course, and involving, also, a damaging strain upon the 35 connection. For avoiding all these objections I place in the length of the chain, on each side and preferably near the axle, an elastic spring, f, of either a spiral piece of metal or a block of rubber. This may be in the nature of an elas- 40 tic link in the chain, as shown, or it may be a spring attached directly to the axle on each side of its central pivot. This, it will be seen, allows the chain to give and compensate for the unequal winding or play in the axle and steer- 45 ing-connections, and if one or both wheels strike an obstruction the springs relieve the gears and steering-chains of strain, and also imme- diately restore the axle to its proper position.

For connecting the boiler to the front axle 50 a box-plate, L, has a curved upper surface adapted to fit the bottom of the boiler, and is slotted lengthwise the boiler, as in Fig. 4, and is connected to the boiler by shoulder-bolts m, which, when screwed to the boiler tight, allow 55 the latter to move lengthwise of the plate to compensate for expansion. This box-plate L is bolted or riveted between the forward ends of the side sills, A A, and is connected with a

yoke-plate, M, by a vertical bolt, n, about which the circular upper end of the yoke M turns, af- 60 ter the manner of a fifth-wheel. This yoke-plate receives a cap-plate, N, which passes through it and is fulcrumed to it by a bolt, o. This cap-plate has two chambers, one upon 65 each side of its fulcrum, in which are contained springs p p, that bear upon the axle of the front wheels. This axle H passes through the cap-plate N, and is provided with two clips, q q, which are rigidly connected with the axle, and serve to hold the cap-plate in proper position 70 upon the axle.

P is a brace, which extends from the bottom of the yoke-plate M to the sills A A, for the purpose of resisting the strain involved in running against obstructions.

Having described my invention, what I claim as new is—

1. The side sills, A A, made longer than the boiler, and combined with the same by strap or straps C and a single rigid connection, a, and 80 extending in rear of the boiler, substantially as and for the purpose described.

2. The combination, with the axle E and the engine-frame G, connecting and supporting both the main shaft and cylinder, of the side 85 plates, D, arranged to support the rear end of the engine-frame and carry the weight and strain of the working parts of the engine and traction-gearing and relieve the boiler, sub- stantially as described.

3. The combination, with the boiler and the axle E, of the side plates, D, and the engine-frame G, resting at one end upon the side plates, and at the other connected to and resting upon the boiler through an expansion-joint, 95 as described.

4. The combination, with the boiler, of the sills A, connected to and sustaining the rear end of the same by a strap or straps, C, and connected to the boiler at their front ends by 100 an expansion-joint, as described.

5. The combination, in a road-engine with a pivoted front axle and the chain-gear, of a spring-connection for said chain, as and for the purpose described.

6. The combination of the axle H, spring- seated cap N, the yoke-plate M, and the box- plate L, the box-plate and yoke-plate being connected by a vertical pivot-bolt, and the yoke- plate and cap-plate being connected by a horizontal fulcrum-bolt, substantially as described.
